UNITED STATES PATENT OFFICE.

CHARLES M. LEECH, OF LIMA, OHIO.

GAS-ENGINE.

No. 914,292.

Specification of Letters Patent. Patented March 2, 1909.

Application filed February 5, 1907. Serial No. 355,838.

To all whom it may concern:

Be it known that I, CHARLES M. LEECH, a citizen of the United States, residing at Lima, in the county of Allen and State of Ohio, have invented certain new and useful Improvements in Gas-Engines, of which the following is a specification

This invention relates to new and useful improvements in gas engines and it has particular reference to engines comprising independent explosion, compression and crank chambers.

The invention aims as a primary object to provide in connection with an engine of the above type, novel means for cooling the engine cylinder and the piston, in which air is relied upon as the cooling agent.

The invention aims as a further object to provide in connection with the elements above set forth, novel lubricating means including an oil pump, the plunger of which forms a part of the piston transmission of the engine *per se* and in which the crank case is preferably utilized as an oil reservoir.

Still another object of the invention is to provide novel means for guiding and centering the piston of the engine in its movement and to preserve the proper alinement of the associated parts.

The invention aims as a further object to provide in an engine of the two-cycle type, novel means for allowing of an increased area of compression, such means particularly residing in the novel features of construction of the piston, and compression chamber.

The detailed construction will appear in the course of the following description in which reference is had to the accompanying drawings forming a part of this specification, like characters of reference designating similar parts throughout the several views, wherein,

Figure 1 represents a battery comprising two engines constructed in accordance with my invention and connected to the same crank shaft, one of the engines being shown in front elevation and the other in central vertical section. Fig. 2 is a central vertical section taken at right angles to Fig. 1 and showing the engine piston in its lowermost position. Fig. 3 is a horizontal section on the line 3-3 of Fig. 2, illustrating in detail the construction of the air cooling jacket applied to the upper part of the engine cylinder, and, Fig. 4 is a horizontal section on the line 4-4 of Fig. 2, illustrating the

construction of the piston, compression chamber and valve controlled fuel passage between the compression chamber and the explosion chamber.

The engine constituted in the present invention comprises a casting 1 having an enlarged lower portion 2 forming the compression chamber and a reduced upper portion 3 forming the explosion chamber and having its exterior surface provided with radial vertical fins 4 for facilitating the circulation of air which is relied upon to cool the chamber 3. Said chamber is formed centrally of its upper portion with a boss 5 having an internally threaded aperture 6 extending therethrough for the reception of a spark plug. Surrounding the chamber 3 is a jacket 7 which is spaced away from the edges of the fins 4, the lower edge of said jacket resting on the shelf 8 afforded by the upper portion of the compression chamber 2, and being held from displacement by retaining flanges 9 provided on said shelf, and engaging said jacket as is best shown in Fig. 1. The jacket 7 is formed in its top with an opening 10 surrounding the boss 5 and affording an air admission and exhaust means. The chamber 3 at its upper end is provided with raised bosses 11 arranged at suitable intervals and designed to receive bolt and nut fastenings 12, by means of which the jacket 7 is fixed to said chamber.

The crank case is formed in two sections, an upper section 13 and a lower section 14. These sections are provided with confronting flanges 15 which are bolted together by fastening means 16. In their assembled relation, the sections 13 and 14, aside from their function of constituting the crank case, afford an oil chamber, the section 14 being provided with an oil drain opening 17, which may be controlled by a suitable cock (not shown). The section 13 at its upper portion, is formed with a vertical annular boss 18 which is threaded internally and externally, for connection with the chamber 2 and with an oil pump cylinder 19, respectively. The cylinder 19 projects into the chamber 2 and overlies the air and gas inlet port 20, provided at one side of said chamber. The sections 13 and 14 are so shaped as to form a closed cylindrical crank case. Said sections are recessed along the confronting edges of their side walls to form centrally located bearings 21 for the power shaft 22, of a single engine or of a battery. When a battery of

engines is employed, said power shaft is enclosed by upper and lower semi-annular members 23 having confronting flanges 24 and united to one another by bolt and nut 5 fastenings 25. The members 23 at their outer edges are provided with angular flanges 26 which are bolted by fastenings 27 to the adjacent crank cases on either side thereof.

The piston comprises a hollow cylindrical body 28, the upper portion of which is confined within the explosion chamber 2 and packed by suitable rings 29. The piston 28 has a reduced upper head 30, against which the ignited exploding charge impinges and an 10 enlarged lower head 31 which is confined within the chamber 2 and is packed by rings 32. The heads 30 and 31 are apertured centrally and receive therethrough the piston rod 33, which is threaded as at 34, through 15 said apertures. Said piston rod is formed with an enlarged cylindrical lower end 35, which projects into the cylinder or barrel 19 and constitutes the plunger of the oil pump as above intimated. The plunger 35 has a 20 central transverse bore within which is disposed a wrist pin 36, the latter being fixed against rotation by set screws 37 threaded through the underneathe face of said plunger and frictionally engaging said wrist pin as is 25 shown in Fig. 1. The shaft 22 within the crank case has a crank 38 which is connected by a pitman 39 with the wrist pin 36, said pitman terminating at both ends in sleeves 40 which surround respective wrist pin 36 30 and crank 38 and which are packed by interposed cylindrical bushings 41.

As previously stated the jacket 7 has a central air admission and exhaust opening 10. The shelf 8, which forms the bottom of 40 said jacket is provided with a plurality of openings 42, preferably disposed between the fins 4 and communicating with the upper part of the compression chamber 2. The air from the openings 42 impinges directly 45 upon the compression head 31. The piston 28 above said compression head is formed with openings 43, communicating with the interior thereof, whereby the air from the openings 42 may circulate therethrough and 50 act upon the piston 28 with cooling effects, both from the interior and exterior thereof.

As previously stated, the crank case constitutes an oil reservoir and in this relation forms one element of an automatic lubricating pump, the plunger 35 of which, as will be readily understood works coincidently with the piston 28. The compression chamber 2 is provided at opposite sides with longitudinal oil ducts 44, which at their upper ends are 55 continued at an angle as at 45 beneath the openings 42 and which are designed to communicate with the openings 43 in the piston 28, when the latter is in its uppermost position, as shown in Fig. 1. The oil ducts 44 are 60 fed from an oil cup 44° located at one side of

the casing, and communicating with one of said ducts at its upper end and adjacent its angular portion 45. The reciprocation of the piston causes the upward and downward movement of its lower plunger portion 35, 70 within the barrel 19, which plunger causes a vacuum within the crank case, and sucks air and oil downwardly through the ducts 44 from the jacket 7, and oil cup 44° respectively, thus lubricating the wrist pin 36 of said 75 plunger 35 when the opening 49 of said wrist pin moves into alinement with the groove 48 at the base of the ducts 44. It will thus be seen that upon the downward movement of the plunger 35, the air previously drawn 80 into the crank case will be forced upwardly through ducts 44, carrying a portion of the oil therein, upwardly within the angular portions 45 of said ducts, from where a portion of such oil will be subsequently sucked down- 85 wardly through openings 62 to lubricate the lower piston head 31 and a portion also of said oil will be forced against the piston 28 to lubricate the exterior thereof, and a further portion will be forced within the openings 90 43 of said oil piston when said openings come into alinement with the angular upper members 45 of said oil ducts 44. Thus it will be further seen that the oil forced within the oil piston through openings 43 will collect there- 95 in until sufficient has accumulated to run out of the openings upon the opposite side, and be sucked downwardly through the opposite duct 44 to assist in the lubrication of the plunger 35, its wrist pin 36, and its barrel 19. 100 It will also be understood that the oil carried within the crank case will be splashed by the action of the crank 38 and will lubricate said crank and assist in the lubrication of the barrel 19. The wrist pin 36 is formed with 105 an axial opening 49 extending therethrough and having a central branch 50 leading to the surface thereof, so that the oil admitted through each end of the wrist pin when the said opening 40 is in registry with the opening 47 and groove 48 will be conducted by way of the opening 49 and branch 50 to the surface of said wrist pin and to the inner surface of the bushing 41. It will be readily appreciated that by the above arrangement 110 of parts, all the movable elements are at all times during the action of the engine, thoroughly and efficiently lubricated.

As previously stated the compression chamber 2 is formed with an enlarged port 115 20 for the admission into said chamber of air and gas. It will of course be understood that the conductor communicating with said port is controlled by a suitable back pressure or check valve. At a point opposite the 120 port 20, the chamber 2 is formed in its lower portion with a similar port 51, which 125 communicates with a vertical passage 52 leading into the explosion chamber 3. The passage 52 is controlled by a rotary throttle valve 130

53, which is preferably in the form of a turning plug and works in a conformable seat 54, provided therefor in the casting 1. The valve chamber thus afforded, is provided at 5 its ends with removable plugs 55 which are preferably threaded thereinto and which hold the valve 53 against axial displacement or play. Said valve carries at one end a stem 56 which is projected through the adjacent plug 55 and which carries at its extremity an arm 57 for connection with a suitable controlling mechanism or lever. The valve 53 is formed with a recessed opening 58, co-extensive in width with the passage 15 52. The explosion chamber 3 is provided at a point opposite the point of communication of the passage 52 therewith, with an enlarged exhaust port 59 threaded as at 60 for connection with a suitable conductor, the latter 20 being of course, valve controlled. The passage 52 and the port 59 communicate with the chamber 3 at a point above the shelf 8. The space between said ports and said shelf is jacketed as at 61, the jacket 61 communicating with the chamber 2 through suitably arranged openings 62. In order to permit of the passage 52 being of sufficient width, the casting 1 is formed adjacent its chamber 2 with an enlarged off-set portion 63 within 30 which said passage occurs as is shown in Figs. 2 and 3. The piston 28 is formed along its upper surface with a semi-annular deflector 64 for directing the force of the explosive charge in the proper direction.

35 It is believed that the operation of the various details of the invention will be readily understood from the foregoing description. The operation of the oil pumping mechanism has been set forth at length. The piston 40 28 not only serves the functions for which it was primarily designed, but it likewise serves as an air pump plunger to force a circulation of air from without the engine through the interior thereof. On the downward stroke of the piston cold air is drawn 45 through the opening 10, between the pins 4, through the openings 42, into the compression chamber 2, where it acts upon said compression chamber and upon the explosion chamber 3. The air thus admitted into the compression chamber likewise acts with cooling effect upon the compression head 31 of the piston 28 and upon the inner and outer surfaces of said piston in the manner previously described. The compression chamber 2 is cooled by the air confined therewithin. The explosion chamber 3 is cooled by the air circulating between the fins 4 and confined by the jacket 7. The piston 50 28 on its upward stroke forces the spent air through the openings 42 and the jacket 7, out of the opening 10. It will thus be seen that a continuous circulation of cold air is afforded for the purposes specified.

55 The arrangement of the oil pump with

relation to the working parts is such that firing of the oil, both in the cylinder and in the crank case, is positively prevented. In addition to this advantage the feed is constant and uniform. The arrangement 70 of the compression chamber with its increased area permits of the development of maximum energy of horsepower. The novel air cooling means possesses the advantage of not requiring for its perfect operation, 75 separate pumps or fans, which are a prominent feature of the art in its present stage of development, nor a multiplicity of controlling valves. This is likewise true of the oil feeding means. 80

The invention is susceptible of various modifications and the construction shown and described is to be regarded in the light of a preferred embodiment or example, rather than of an exclusive type. 85

The invention resides, not so much in the construction of the detailed elements as in the combination of the oil pumping means, and the air pumping and cooling means together with the other broad features of construction set forth. 90

It is to be noted that the cylinder or barrel 19 owing to its concentric and axial relation to the cylinder and to the piston working therein, serves incidentally as a guide for 95 said piston and its associated parts. The arrangement of this barrel may be varied considerably from the disclosure. Various changes may likewise be made in the several other elements described, both as regards arrangement, and construction, without departing from the spirit and scope of the invention as defined in the appended claims. 100

Having fully described my invention I 105 claim:

1. A gas engine comprising a cylinder, a hollow piston operating in said cylinder and dividing the same into compression and explosion chambers, said piston having an air 110 opening through its wall, and a jacket surrounding said explosion chamber having an opening for the admission of air therein, said cylinder having an opening therethrough between said compression and explosion chambers and communicating between said jacket and said piston openings, substantially as described. 115

2. A gas engine comprising a cylinder, a hollow piston operating in said cylinder and dividing the same into compression and explosion chambers, said piston having an air opening through its wall, and a jacket surrounding said explosion chamber having an opening for the admission of air therein, said cylinder having openings therethrough communicating between said jacket and said piston openings and between said jacket and said compression chamber, substantially as described. 120 125 130

3. A gas engine comprising a cylinder, a hollow piston operating in said cylinder and dividing the same into a compression chamber and an explosion chamber above said compression chamber and of reduced diameter thereto, the upper portion of said compression chamber constituting a shelf, a jacket surrounding said explosion chamber and resting upon said shelf, said piston having an air opening through its wall, said jacket having an air admission opening therein, and said shelf having intercommunicating opening therethrough extending between said jacket and said compression chamber and between said jacket and said piston openings, substantially as described.

4. A gas engine comprising a cylinder provided with a lower central pump barrel, a piston operating in said cylinder, said cylinder being provided with openings through its wall communicating between said barrel and the said piston, an oil supply in connection with said wall openings, and a pump piston connected to said cylinder piston, and operating within said barrel to guide said cylinder

piston in its stroke, and to force oil from said supply through said openings to said cylinder piston and said barrel, substantially as described.

5. A gas engine comprising a cylinder, a piston operating in said cylinder and dividing the same into compression and explosion chambers, said cylinder being provided with a central pump barrel below said chambers, and with openings through its wall communicating between said barrel and said compression and explosion chambers, an oil supply in connection with said wall openings, and a pump piston operating within said barrel and connected to said cylinder piston to force oil from said supply through said openings, and into said chambers, substantially as described.

In testimony whereof I affix my signature in presence of two witnesses.

CHARLES M. LEECH.
